UNITED STATES PATENT OFFICE.

JOHN F. HARRIS, OF FRACKVILLE, PENNSYLVANIA.

AIR-SHIP.

No. 836,577.

Specification of Letters Patent.

Patented Nov. 20, 1906.

Application filed September 29, 1905. Serial No. 280,657.

To all whom it may concern:

Be it known that I, JOHN F. HARRIS, a citizen of the United States, residing at Frackville, in the county of Schuylkill and State of Pennsylvania, have invented certain new and useful Improvements in Air-Ships; and I do declare the following to be a full, clear, and exact description of the invention, such as will enable others skilled in the art to 10 which it appertains to make and use the same.

My invention relates to improvements in air-ships; and it consists in the novel construction, combination, and arrangement of 15 devices hereinafter described and claimed.

The object of the invention is to improve and simplify the construction and operation of machines of this character, and thereby render the same more durable and efficient.

20 The above and other objects, which will appear as the nature of my invention is better understood, are accomplished by means of the construction illustrated in the accompanying drawings, in which—

25 Figure 1 is a vertical longitudinal sectional view through an air-ship constructed in accordance with my invention. Fig. 2 is a vertical transverse sectional view taken on the plane indicated by the line 22 in Fig. 1; and 30 Fig. 3 is an end elevation of a portion of the ship, showing the swinging door in one end of the air chamber or compartment.

Referring to the drawings by numeral, 1 denotes the body portion of my improved 35 air-ship, which comprises a lower motor room or chamber 2 and air room or chamber 3, which is disposed above and separated from the chamber 2 by a partition 4, an upper steering room or chamber 5, located above 40 the chamber 3, and a gas chamber or bag 6, which is disposed above the chamber 5 and is adapted to float or support the ship. Light and air are admitted into the chambers or compartments 2, 3, and 5 through suitably-covered openings 7, and access may be had from one of said chambers or compartments to the other by means of flights of stairs or the like 8, arranged in the chambers 2 and 3, as clearly shown in Fig. 1 of the drawings. 45 Suitable doors 9 are also provided in the side of said chambers or compartments to permit persons to enter and leave them, and around the steering room or chamber 5, upon the top 10 of the chamber 3, I preferably provide a 50 railing 11, as shown. The gas-chamber 6

may be of any desired form and construction. In the lower chamber or compartment 2 is provided a motor 12, which may be of any desired form and construction and which has one end of its shafts projecting through one 60 end of the said chamber and carrying a rotary propeller 13. At the adjacent end of the steering chamber or compartment 5 is pivotally mounted a rudder 14, which is controlled by any suitable mechanism, as shown 65 at 15 in Fig. 1.

The ship is adapted to be floated by the balloon or gas-bag 6; but in order to assist the same and also the propeller 7 and rudder 8 in propelling and steering the ship I provide means for forcing a current of air out of either or both ends of the chamber or compartment 3. As shown, I accomplish this by providing a rotary fan or blower 16 in the motor-chamber 2 and connect the same by a 70 pipe 17 to the air chamber or compartment 3. The shaft of the fan 15 is preferably connected up with the shaft of the motor 9, as shown at 18, and connected up with said motor-shaft by means of an endless belt or cable 19. 75 Another rotary fan or blower 20, which is preferably mounted on a transversely-extending shaft 21, journaled in bearings upon the floor of the chamber 3. The outlet 22^a 80 of the casing, which surrounds the fan 20, 85 projects in opposite directions toward the ends of the chamber 3. One may also be provided which communicates with the pipe 17, and at their juncture are provided two oppositely-projecting discharge-pipes 22. 90 The ends of the chamber or compartment 3 are open and are adapted to be closed by swinging doors 23, which are hingedly mounted at their upper ends to uprights 24, arranged upon the opposite sides of the door- 95 openings in the ends of said chamber 3. Pivotaly mounted, as shown at 25 in Fig. 3 of the drawings, are cross-bars 26, which have depending from their central portions arms 27, against which the doors are adapted to 100 swing. To said arms 27 are connected the ends of operating cords or cables 28, which pass through openings in said doors and over guide-pulleys 29, arranged as shown in Fig. 1. It will be seen that when the cords 28 are 105 drawn upon the arms 27 will engage the doors 23 and hold them in their closed position and that when they are released the current of air from the pipes 22 and 22^a will 110 swing them open to permit the air to dis-

charge from the ends of the chamber 3, and thereby assist the propeller and the gas-bag in propelling and floating the ship.

In the top 10 of the room or compartment 3 are mounted sliding frames 30. These frames are mounted to slide horizontally and may be moved into and out of said chamber by means of cables 31, which are passed over suitable guide-pulleys 32, as shown. When the frames are in their projected position, as shown in dotted lines in Fig. 2, they are adapted to serve the purpose of parachutes and permit the ship to descend gradually.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of this invention.

Having thus described my invention, what I claim as new, and desire to secure by Letters Patent, is—

1. An air-ship having a body provided with a chamber open at its front and rear

ends and provided with closures for said ends, and means to open and close said closures, a blower in said chamber having discharge-pipes projecting toward the ends thereof, and a motor to drive said blower.

2. An air-ship having a body provided with a chamber open at its front and rear ends and provided with closures for said ends, and means to open and close said closures, a blower in said chamber having discharge-pipes projecting toward the ends thereof, a motor-chamber below the first-named chamber, a motor in said motor-chamber, a blower also in the motor-chamber, a pipe leading from said blower to that in the first-named chamber and having forwardly and rearwardly projecting discharge-pipes at the juncture therewith, a propeller, and a motor in the motor-chamber connected to and operating the propeller and the said blowers, substantially as described.

In testimony whereof I have hereunto set my hand in presence of two subscribing witnesses.

JOHN F. HARRIS.
